UNITED STATES PATENT OFFICE.

FRANK DORCHEK, OF COLORADO SPRINGS, COLORADO.

GROCERYMAN'S BOX.

1,348,552.

Specification of Letters Patent.

Patented Aug. 3, 1920.

Application filed April 5, 1919. Serial No. 287,851.

To all whom it may concern:

Be it known that I, FRANK DORCHEK, a citizen of Czechoslovakia, residing at Colorado Springs, in the county of El Paso and State of Colorado, have invented certain new and useful Improvements in Grocerymen's Boxes, of which the following is a specification.

The primary object of the invention is to provide means adapted for household use by which the goods left at a house door by a vender will be safe against theft until removed by the housekeeper.

A further object of the invention is the provision of holding means for groceries and the like adapted for mounting upon a convenient support such as a door post of a house and wherein articles such as groceries and milk may be deposited, the device being automatically locked upon closing the same and unlocked when the owner removes the locks therefrom.

With these general objects in view, the invention consists of the combination and arrangement of parts hereinafter fully described in connection with the accompanying drawings and in which like reference characters designate corresponding parts throughout the several views,

30 In the drawings,

Figure 1 is a vertical longitudinal sectional view taken upon line III—III of Fig. 2,

Fig. 2 is a horizontal sectional view of the same,

Fig. 3 is a view similar to Fig. 1 with the door in its closed and locked position, parts being shown in elevation,

Fig. 4 is a vertical transverse sectional view taken upon line VI—VI of Fig. 1,

Fig. 5 is a perspective view of the door detached,

Fig. 6 is a perspective view of the latch for the door detached.

45 Referring more in detail to the drawings, my invention broadly includes a casing in the form of a box 10 having an opening 11 in the front thereof adapted to admit such articles as groceries and bottles of milk,

50 while a hinged door 12 is provided for the opening 11. The door is normally maintained open by a latch mechanism hereinafter described adapted to be released by a sliding pin 13 at one end of the box 10, an oppositely positioned locking bolt 14 being provided for the door. A hinged door 15

in the top 16 of the box 10 is normally locked closed by a padlock 17.

A staple 18 upon the rear edge of the door 12 is provided with a pivoted bar 19 slidable upon a guard 20 carried by a plate 21 upon the inner face of the front wall 22 of the box with a spring 23 extending through a slot 24 of the said bar adapted for swinging the door 12 to its closed position upon its hinges 25.

A pivoted latch 26 upon the plate 21 is connected by means of a link 27 with a lever 28 also pivoted upon the plate 21 with one end of said lever constantly engaged by the inner end of the aforementioned pin 13. A leaf spring 29 normally holds the inner end of the pin 13 against the adjacent end of the lever 28 while a similar spring 30 bearing upon the latch 26 normally maintains the latch engaging the upper face of the bar 19 and projected within a notch 31 in the upper face of the bar when the door 12 is open as illustrated in Fig. 3 of the drawings. It will be apparent that upon forcing the pin 30 80 13 inwardly, the latch 26 will be released from the notch 31 and permitting the spring 23 to swing the door 12 to its closed position.

A platform or false bottom 32 is positioned within the box 10 beneath the level 85 of the front entrance opening 11, the same being resiliently mounted upon a plurality of springs 33 extending longitudinally and secured as at 34 to the bottom 35 of the box. The springs 33 normally maintain the platform 32 horizontally positioned engaging beneath opposite cleats 36 upon the end walls 37 of the box, while an anti-friction roller 38 is journaled in each end of the platform 32 adjacent said end walls. 95

The locking bolt 14 for the door 12 is slidably mounted in a guide plate 39 carried by the front wall 22 of the box at the opposite side of the opening 11 from the latch 26. The bolt 14 is adapted to be projected into a keeper socket 40 provided in the free end 100 of the door 12, the bolt being normally held retracted when the box 10 is empty in the manner hereinafter set forth.

A detent or foot 41 is pivoted as at 42 in 105 a transverse slot 43 provided substantially centrally in the bottom 35 of the box, a coiled spring 44 having one end anchored as at 45 in the rear end of the slot and with the other end of the spring 44 attached to a lug 46 110 upon the detent 41. The said detent is normally maintained pressed against the bottom

of the platform 32 by means of said spring 44. An angular slot 47 communicates with the slot 43 and extends to an upright slot 48 in the front wall 22. A lever 49 in the slot 47 is pivoted at 50 to the bottom 35 and connected by a wire rod 51 with a lug 52 upon the end face of the detent 41. An angular rocker 53 is pivoted at 54 in the slot 48 with the upper end of the rocker operatively engaging within a side notch 55 of the bolt 14. An angular arm 56 pivoted in the slot 47 is pivotally connected by a link 57 with the adjacent end of the lever 49 and with the lower adjacent end of the rocker 53 by means of a pivoting link 58.

From this detailed description of the mechanism, it will be apparent that upon placing a package such as 59 upon the platform 32 through the opening 11, the bolt 14 will be automatically projected into the opening 11 so that upon releasing the latch 26 by inwardly pressing the pin 13, the door will be automatically closed by the spring 23 engaging the bolt 14 within the keeper member 40 heretofore noted. The owner of the box 10 such as a housewife, may then release the lock 17 and remove the package 59 whereupon the springs 33 will automatically elevate the platform to its normal position 30 while the spring 44 will retract the bolt 14

permitting the door 12 to be manually opened, it being seen that the latch 26 automatically seats within the notch 31 when the door is in its open position. The lock 17 is again secured and the box 10 is again ready to receive vended articles for retaining the same safely against theft although readily removed by the owner upon releasing the padlock 17.

What I claim as new is:

A device of the class described comprising a box having a forward entrance opening, a door for the entrance opening, a bar slidably mounted within the box having a link connection at one of its ends with said door, tensioned means associated with the other end of said bar for normally holding the door in its closed position, a tensioned bell crank lever pivoted within said box adapted to engage the sliding bar to hold the same projected against the tension of the resilient means connected to said bar with the door in its open position and manually operable means for said bell crank lever to release the same from said bar to permit the bar tensioning means to operate said bar and close the door.

In testimony whereof I affix my signature.

FRANK DORCHEK.
